UNITED STATES PATENT OFFICE.

WILLIAM MAIER, OF BUFFALO, NEW YORK, ASSIGNOR OF ONE-THIRD TO HIMSELF, ONE-THIRD TO SETH H. KOOPMANS, AND ONE-THIRD TO HENRY R. HOFFIELD, OF BUFFALO, NEW YORK.

CASTER.

932,038.

Specification of Letters Patent. Patented Aug. 24, 1909.

Application filed May 6, 1905, Serial No. 259,105. Renewed January 20, 1909. Serial No. 473,264.

To all whom it may concern:

Be it known that I, WILLIAM MAIER, a citizen of the United States, residing at Buffalo, in the county of Erie and State 5 of New York, have invented certain new and useful Improvements in Casters, of which the following is a specification.

This invention relates to an improved caster for furniture and the like and particularly to the construction of the roller 10 which consists of a core and an annular covering of felt which is forced over the core from at least one end thereof and is secured to the periphery of said core with 15 glue or the like.

The object of the invention is to provide a roller having a soft peripheral covering which is rigidly fastened thereon, and which may be placed upon furniture located in 20 rooms having polished hard wood floors to prevent injury to the floors.

The invention also relates to certain details of construction, all of which will be fully and clearly hereinafter described and 25 claimed, reference being had to the accompanying drawings, in which,—

Figure 1 is a side view of the improved caster. Fig. 2 is a central vertical section through the caster. Fig. 3 is an enlarged 30 detached side view of the roller. Fig. 4 is a detached section through the core on line *a a*, Fig. 11. Fig. 5 is a detached section through the core on line *b b*, Fig. 11. Fig. 6 is a diametrical section through the core 35 on line *c c*, Fig. 5. Fig. 7 is a detached edge view of the roller. Fig. 8 is a central section on line *d d*, Fig. 3. Fig. 9 is a diametrical section through the core on line *e e*, Fig. 5. Fig. 10 is a section through the 40 roller on line *f f*, Fig. 8. Fig. 11 is a detached edge view of one form of roller having both circumferential and transverse 45 grooves. Fig. 12 is a detached edge view of another form of roller having both circumferential and diagonally extending grooves.

In referring to the drawings for the details of construction, like numerals designate like parts.

50 The caster shown in Figs. 1 and 2, consists of a shank 1, having an enlarged head 2, and a bifurcated foot 3, between the forks of which a roller is journaled on a shaft 4, and a sleeve 5, having a flanged or enlarged

lower end 6, and a reduced and slotted upper 55 portion 7, which is sprung over the head 2, of the shank when the shank is inserted in the sleeve. The sleeve 5, is fitted in a recess in the lower end of the leg of a chair or other suitable article in the usual manner 60 with the flange 6, fitting against the end thereof. The roller consists of a core 8, which is preferably constructed of wood although it may be made of any other suitable material and a peripheral covering 9, 65 of felt or the like. The core is provided with a series of peripheral grooves which serve to retain the glue or other adhesive employed to fasten the covering 9, in place. These grooves may extend circumferentially 70 around the core or transversely or diagonally across the periphery thereof or a plurality of either of these differently extending grooves may be utilized, either alone by themselves or in conjunction with others. 75 On the drawings the circumferential grooves are designated by the numeral 10, the transverse grooves by the numeral 11, and the diagonal grooves by the numeral 12.

The covering 9, is preferably formed in 80 two annular halves of felt and in securing the covering in place, the grooved periphery of the core is first covered with glue and the two annular halves which are slightly 85 smaller in their circumference than the core, are slightly stretched and forced over opposite ends of the core toward each other until their edges contact. The covered core is then placed in a compressing mechanism which entirely surrounds it and the covering 90 is pressed firmly upon the serrated surface of the core and held in compressed position thereon until the glue is set. This operation forces portions of the felt into the serrations and into close contact with 95 the surface of the core so that the opposed surfaces of the core and covering will be very firmly united by the glue or other adhesive employed. The object of this is to prevent the glue being forced off the surface of the core as the felt is fitted on. This is the disadvantage of a broad one piece felt ring which as it is stretched and fitted over one end of the core and pushed on presses 100 closely against the core surface and collects the glue on the surface of the core in front of it as it is moved laterally upon the core and forces it off the opposite end, always 105

removing the greater portion of the glue and not leaving enough on the core surface to properly secure the felt to the core.

The chief advantages of this invention reside in the soft surfaced roller, the two part construction of the felt covering and the firm manner of securing the same to the core.

I claim as my invention.

- 10 1. In combination in a roller, a core having a series of peripheral circumferential and transverse grooves to retain glue and an annular felt covering surrounding and glued to said core.
- 15 2. In combination in a roller, a core hav-

ing a series of peripheral grooves, some of which extend circumferentially around the core and others of which extend at an angle to said circumferential grooves and an annular covering of felt glued to said core.

3. In combination in a roller, a core having a plurality of peripheral grooves some of which extend at angles to others and a plurality of annular felt rings glued side by side to and covering the periphery of said core.

WILLIAM MAIER.
